UNITED STATES PATENT OFFICE.

JAMES C. DAWSON, OF WEBSTER GROVES, MISSOURI, ASSIGNOR TO GEORGE D. BARNARD & CO., OF ST. LOUIS, MISSOURI, A CORPORATION OF ILLINOIS.

LOOSE-LEAF BINDER.

1,077,681.

Specification of Letters Patent.

Patented Nov. 4, 1913.

Application filed November 11, 1912. Serial No. 730,693.

To all whom it may concern:

Be it known that I, JAMES C. DAWSON, a citizen of the United States, and resident of Webster Groves, county of St. Louis, and 5 State of Missouri, have invented certain new and useful Improvements in Loose-Leaf Binders, of which the following is a specification, and which are illustrated in the accompanying drawings, forming a part 10 thereof.

The invention relates to loose leaf binders, and more particularly to those having a pair of upright filing posts with one of the posts movable and provided with an overhanging 15 top for telescopically engaging the higher end of the other post.

The object of the invention is to provide a binder of this type which shall be of simple and improved construction and reliable 20 in operation.

The invention is exemplified in the structure to be hereinafter described, and which is illustrated in the accompanying drawings, wherein—

25 Figure 1 is a perspective view showing a loose leaf binder embodying features of improvement provided by the invention; Fig. 2 is similar to Fig. 1 but has some of the parts broken away to show the internal 30 construction; and Fig. 3 is a detail longitudinal sectional view of the binder.

For the purpose of illustrating the invention there is shown a binder adapted to receive adjustable leaves of the sort shown 35 in the patent to Anderson No. 879,135, dated February 18, 1908, and having dumb-bell shaped filing apertures. The parts of the binder are shown as being associated upon a base plate 10. This base plate, together 40 with a top plate shown at 11, serve as covers for the sheets 12. As already indicated, the sheets 12 are punched with dumb-bell shaped apertures shown at 13 and 14 (Fig. 1). In practice the sheets 12 are filed upon upright 45 posts arranged in pairs, as 15, 16 and 17, 18, the posts of each pair being normally connected at their higher ends by arches, represented at 19 and 20. To permit the sheets to be shifted in position in the binder, 50 the arches 19, 20 are of flattened cross section to receive the contracted portion of the dumb-bell shaped apertures 13, 14.

In carrying out the present invention the arches 19 and 20 are each formed integral 55 with one of the posts, as 16, 18, and these

posts are movably mounted to bring the free ends of the arches into and out of engagement with the posts 15 and 17 respectively. By means of this arrangement complete rigid filing arches are formed, and there 60 is but one joint between the parts of the arches over which the sheets must be passed in transferring them from side to side on the binder.

A base member 21 preferably constructed 65 in the form of an inverted channel and having closed ends, serves for supporting the filing posts. The upper surface of this base member is preferably flush with the upper surface of the base plate 10 to provide a smooth 70 support for the sheets to be filed. For this purpose the base plate 10 is rabbeted adjacent one end to provide a seat 22 for receiving the flattened tubular base member 21. Screws shown at 23 serve for securing 75 the base member 21 upon said seat.

Preferably the posts 15 and 17 are stationarily mounted, as by being rigidly secured at their lower ends upon the wall of the base member 21. The posts 16 and 18 80 are mounted to swing upwardly and outwardly. As shown, these posts rise from a plate 24 inclosed within the chamber of the base member 21, and pass through slotted openings 25 in the upper wall of said base 85 member. The plate 24 is movably mounted by being provided with a trunnion 26 at each end. These trunnions are each engaged with a vertically slotted bearing block 27 fixed in position within the chamber 90 of the base member 21.

To provide a firm connection between the two posts, as 15, 16 and 17, 18 of each pair when the binder is closed, the free end of each of the arches 19, 20 is of reduced diameter to form a stud 28, and the posts 15, 17 are each provided with a socket 29 at their higher ends for receiving the corresponding studs. The binder mechanism is opened by lifting the arches 19, 20 to raise 100 the studs 28 out of engagement with the sockets 29 and by then swinging the posts 16, 18 away from the posts 15, 17 to the position indicated by dotted lines in Fig. 3. This movement of the posts is accompanied 105 by a rising and turning movement of the plate 24, which movement is accommodated by the slotted form of the bearings 27.

Most desirably a key-operated mechanism 110 is provided for holding the parts of the

binder in closed position. To this end, a locking plate 30 is slidably mounted within the chamber of the tubular base member 21. The sliding movement of the locking plate 30 is guided and limited by means of guide pins 31 each of which is fixed in position within the chamber of the base member 21 and passes through a slotted opening 32 in the locking plate 30. The plate 24 is provided with lateral extensions 33 and 34, and the plate is locked against movement for holding the filing arch members in closed position, by moving the locking plate 30 over the lateral extensions 33, 34 of the plate 24.

A screw-threaded plunger 35 serves for shifting the locking plate 30. As shown, this plunger has threaded engagement with a lug 36 fixed in position within the chamber of the base member 21 and has swiveled connection 37 with the locking plate 30. The outer end of the screw-threaded plunger 35 is shaped for the reception of a key (not shown), and a key-opening 38 is formed in 25 the adjacent end wall of the tubular base member 21 in line with the plunger.

When the binder is to be used, the desired number of sheets 12 are threaded onto the posts 15, 17 and the arches 19, 20 are then 30 closed upon these posts. When a new entry has been made on any one of the sheets 12, such sheet will be shifted in position by raising it into engagement with the arches 19, 20, and then moving the sheet in a direction to pass these arches through the contracted portion of the dumb-bell shaped apertures 13, 14. Sheets which have been shifted in this way will be differentiated from other sheets in the binder by the projection of one edge of the sheet beyond the corresponding side of the remaining sheets, in the manner indicated at 39 (Fig. 2). When it is desired to remove any sheet from the binder, a key (not shown) will be applied to the end of the plunger 35 through the keyhole 38 and the plunger rotated to withdraw the locking plate from engagement with the laterally extended portions 33, 34 of the tilting plate 24.

50. The construction provides a binder having filing arches which are of flattened cross section at the crown whereby the sheets may be shifted in position without opening any of the arches. Furthermore, the arches are held in closed position by a mechanism which is of simple construction and reliable in operation and which permits of the arches being formed with but a single joint over which the leaves must be passed in moving 60 them from one side to the other of the

binder. This last-mentioned feature of the construction is of importance in producing a binder which is reliable in operation, as it is well known that joints in the filing posts or arches of a binder frequently interfere with the movement of the sheets therein.

I claim as my invention—

1. In a loose leaf binder, in combination, a base, a pair of normally upright filing posts, one having an overhanging top and the other post being fixed in the base, the ends of the two posts being constructed for telescopic connection, a pair of trunnions projecting laterally in opposite directions from the lower end of the post having the 75 overhanging top, vertically slotted bearing blocks mounted on the base for receiving the trunnions, an upwardly facing shoulder rigid with the post having the trunnions, and a locking plate movable over the said shoulder when the trunnions occupy the lower ends of the said slots.

2. In a loose leaf binder, in combination, a flattened tubular base having a slotted opening in its wall, a pair of filing posts 80 rising from the base, one thereof being fixed at its lower end in a wall of the base and the other having an integral overhanging top and extending at its lower end through the said slotted opening into the chamber of the base, the higher ends of the two posts being constructed for telescopic connection, a plate within the chamber of the base fixed upon the lower end of the post having the overhanging top, trunnions on the end of 95 the plate, a vertically slotted bearing block fixed within the chamber of the base for receiving each of the trunnions, and a locking plate sliding within the chamber of the base and movable over the first named plate 100 when the trunnions occupy the lower ends of the slots of the said bearing blocks.

3. In a loose leaf binder, in combination, a base, a pair of normally upright filing posts, one having an overhanging top and 105 being connected to the base by a vertically sliding pivot and the other post being fixed in the base, the ends of the two posts being constructed for telescopic connection, an upwardly facing shoulder rigid with the post 110 having the overhanging top, said shoulder being offset from the line of pivotal connection of the post with the base toward the fixed post and a locking plate movable over the said shoulder when the ends of the two 115 posts are in telescopic engagement.
